UNITED STATES PATENT OFFICE.

FRANK BYCROFT KEALL, OF LEICESTER, ENGLAND, ASSIGNOR TO UNITED SHOE MACHINERY COMPANY, OF PATERSON, NEW JERSEY, A CORPORATION OF NEW JERSEY.

SHOE-HOLDING JACK.

1,153,928.

Specification of Letters Patent. Patented Sept. 21, 1915.

Application filed January 20, 1913. Serial No. 743,107.

To all whom it may concern:

Be it known that I, FRANK B. KEALL, a subject of the King of England, residing at Leicester, in the county of Leicester, England, have invented certain Improvements in Shoe-Holding Jacks, of which the following description, in connection with the accompanying drawings, is a specification, like reference characters on the drawings indicating like parts in the several figures.

In certain types of machines for treating shoes, such for example as machines for trimming or burnishing the edges of shoe bottoms, the shoe is clamped in a jack during the operation of the machine thereon. The present invention relates to shoe holding jacks of this general character.

This invention aims to render the processes of jacking or unjacking a shoe more rapid in execution than has been possible with jacks as heretofore constructed; and, more particularly, to devise a clamping mechanism that will hold different sizes and styles of shoes with substantially the same degree of pressure notwithstanding variations in the dimensions of the shoes. One mechanism by which these objects are attained will now be described with the aid of the accompanying drawings which show a jack or work support similar to that described and illustrated in Letters Patent No. 1,078,684, granted November 18, 1913, which patent is assigned to the assignee of the present invention. It must not be assumed, however, that the present invention is confined in its application to a machine of this character or that it is limited to the construction and arrangement specifically described.

In the drawings, Figure 1 is a side view partly in section of a portion of a shoe holding jack showing the mechanism constituting a preferred embodiment of this invention; Fig. 2 is a section on the line 2—2, Fig. 1; Fig. 3 is a perspective view showing in detail the internal construction of the clamping mechanism, certain of the parts being broken away or omitted for the sake of clearness; and Fig. 4 is a view showing in detail part of the mechanism shown in the other figures.

The jack shown comprises a base 2 that is adapted to support the sole of a shoe and a bracket 4 which may be cast integral with the base and has a casing 6 bolted thereto.

This casing has a bore formed therethrough for the reception of a hollow plunger 8 which carries a toe-clamping part 10 that is adapted to bear on the top of the forepart or toe of a shoe resting on the base 2. The toe-clamping member 10 is pivoted at 12 to the lower end of a threaded sleeve 14 which is adapted to slide in the plunger 8, the provision of the pivot for the toe-clamping member 10 and the fact that it is arranged longitudinally of the shoe enabling the member 10 to adjust itself laterally to the curvature of the toe of the shoe.

The sleeve 14 is provided with a flange 16 at its upper end that is adapted to abut against an internal flange 18 on the plunger 8, the latter flange being disposed beneath the flange on the sleeve. Below the internal flange 18 and bearing against the lower surface of the same is a strong helical spring 20 the other end of which presses down upon a collar 22 screwed upon the sleeve 14. By screwing the collar 22 upward or downward the power of the spring may be varied and, as will be seen later in this description, the yielding pressure upon the shoe may thereby be varied according to requirement. A jam nut may be screwed upon the sleeve below the head of the collar 22 to lock the latter in its adjusted position. Preferably, the external diameter of the collar 22 is made to correspond with the internal diameter of the recess in the plunger 8 which receives the spring 20 so that the collar slides within the said recess.

In the bore of the upper part of the plunger 8 two segmental plates 24 are secured, as by screws, each plate being provided with ratchet teeth which project toward the center of the plunger and are adapted to be engaged by one or the other of a pair of pawls 25 and 26 carried by a depending slide member 28. A spring 30 is interposed between the pawls to force their ends outwardly toward the racks. By having two racks with their teeth arranged in a staggered relationship, as shown, and by using pawls of equal lengths, or by maintaining the racks with similarly arranged teeth and providing pawls of slightly different lengths, the equivalent of a rack having fine teeth is obtained and at the same time the construction has greater strength and durability than would be the case if small teeth were employed.

The depending slide member 28 is connected to the lower end of a link 32, the upper end of which is connected to the lower end of an arm 34 forming part of the actuating handle 36, the said handle being formed as a bell crank lever and fulcrumed on a pivot 38 mounted in arms that project upwardly from the casing 6. The link 32 and the arm 34 of the actuating lever together constitute a toggle through which by the actuation of the handle 36 the depending slide member 28 may be raised or lowered. One of the arms of the casing 6 carries a stop 40 against which the toggle bears when in its straightened condition. At its lower end the depending slide member 28 is provided with a cylindrical extension 42 which slides within the bore of the sleeve 14, the slide member 28 above the extension being shaped so as to provide a recess in which the pawls 25 and 26 may swing. Between the bottom of the bore in the sleeve 14 and the lower end of the extension 42 a light spring 44 is positioned. Outwardly projecting shoulders 46 are formed in the member 28 and coöperating shoulders 48 are also provided on each of the rack plates 24 so that as the slide member 28 is raised the plunger 8 will also be lifted through the engagement of these two sets of shoulders. To disengage the pawls 25 and 26 from the racks 24 during the upward movement of the pawls, two stationary deflecting plates 50 are provided, each consisting of a light spring piece hung upon the pivot pin 38, and they extend into the plunger 8 with their ends located between the racks 24 and the shanks of the pawls 25 and 26, respectively, (see Fig. 2).

The operation of the mechanism as above set forth will now be described assuming the parts to be positioned as follows:—The actuating handle 36 is turned so that the toggle 34, 32 is broken and the depending slide member 28 is raised with the pawls 25 and 26 disengaged from the racks 24 by being brought into contact with the stationary depending plates 50 and moved inwardly toward each other. The plunger 8 is also raised through the shoulders 46 of the slide member 28 engaging with the coöperating shoulders 48 of the rack pieces 24, and the sleeve 14 carrying the toe-clamping member 10 also is raised through the engagement of the internal flange 18 on the plunger 8 with the flange 16 on the sleeve 14. The shoe is now placed in position on the support or tread engaging face 2 of the jack with its toe under the clamp 10. The actuating handle 36 is then turned so as to straighten the toggle 34, 32, and cause the parts to assume the positions in which they are shown in the drawings. The first result of this movement of the handle is to cause the slide 28 to move downwardly and through the pressure

of the extension 42 on the light spring 44 to move the clamp 10 into engagement with the toe of the shoe. The sleeve 14, the collar 22, the plunger 8 and racks 24 are all moved downwardly together until the clamp 10 is brought into contact with the toe of the shoe, the extent of depression of these parts depending upon the height of the toe. During this movement the pawls are held out of engagement with the racks by the deflecting members 50, but upon further movement of the actuator 36 the slide 28 is depressed sufficiently to carry the pawls below the ends of the members 50, whereupon one or the other of the pawls engages its co-operating rack thus effecting a driving connection through the strong spring 20 between the actuator 36 and the clamp 10. During this latter movement the sleeve 14 remains substantially stationary in contact with the toe of the shoe, and the extension 42 descends through it, compressing the light spring 44. The final movement of the actuator applies the clamping pressure to the shoe, the amount of this pressure being determined by the adjustment of the spring 20 and the travel of the clamp after the driving connection with the actuator is effected. It will be evident that the racks and pawls constitute in reality a one-way clutch; and that the deflecting members 50 serve to render this clutch inoperative during the greater part of the movement of the actuating handle but permit it to become operative at the same point in each stroke of the handle. Since the handle has a fixed or constant stroke, the extent of the clamping movement imparted to the clamp 10 will be constant except for the very slight difference by which the opposite teeth of the racks are offset or staggered.

Having described my invention what I claim as new and desire to secure by Letters Patent of the United States is:—

1. In a shoe holding jack the combination of a shoe clamp, an actuating member, and connecting mechanism between said clamp and said member for causing said clamp during a portion of the movement of said member to move into engagement with the shoe and thereafter during another portion of the movement of said member to apply a predetermined pressure to the shoe regardless of its size or thickness.
2. In a shoe holding jack the combination of a shoe clamp, an actuating member, connecting mechanism between said clamp and said member for causing said clamp during a portion of the movement of said member to move into engagement with the shoe and thereafter during another portion of the movement of said member to apply a predetermined pressure to the shoe regardless of its size or thickness, and means whereby the degree of pressure may be varied.

3. In a shoe holding jack the combination of a shoe clamp, an actuating member having an operative movement of predetermined extent and having a lost motion connection with said clamp, means operating during a portion of the movement of said member to move said clamp into engagement with the shoe, and means between the actuating member and the clamp, acting from 10 a predetermined point in the operative movement of said actuating member, to drive said clamp.
4. In a shoe holding jack the combination of a shoe clamp, an actuator having an operative movement of predetermined extent, connections between said clamp and actuator for moving the clamp into engagement with the shoe, said connections including a light spring through which the movement 15 of the actuator is transmitted, a strong spring, and means for establishing a driving connection through said strong spring between said actuator and said clamp at a predetermined point in the operative movement of said actuator.
5. In a shoe holding jack the combination of a shoe clamp, an actuator having an operative movement of predetermined extent, means controlled by said actuator for moving 20 said clamp into engagement with the shoe, mechanism including a clutch arranged to effect during said clamping movement a driving connection between said actuator and said clamp, and means for rendering said clutch 25 inoperative during a predetermined portion of the operative movement of said actuator.
6. In a shoe holding jack the combination of a shoe clamp, an actuator having a predetermined stroke, connections between said 30 actuator and said clamp arranged to cause the clamp to move into engagement with the shoe during the first part of the movement of the actuator, said connections including a light spring through which the movement 35 of said actuator is transmitted, a strong spring, means for establishing a driving connection through said strong spring between said actuator and said clamp at substantially the same point in each stroke of 40 the actuator, and means for adjusting the tension of said strong spring.
7. In a shoe holding jack the combination of a shoe support, a shoe clamp mounted for movement toward and from said sup- 45 port, an actuator having a stroke of predetermined extent, connections between said clamp and said actuator including a light spring arranged, upon movement of the actuator, to move the clamp into engagement with a shoe resting on said support, a clutch member connected with said clamp to be positioned by said movement of the clamp, an additional clutch member movable with said actuator and arranged to have a clutching engagement with the other clutch 50 member after said positioning movement of the latter member has been effected, and means to prevent the operative engagement of said clutch members until the actuator arrives at a predetermined point in its 55 stroke.
8. In a shoe holding jack the combination of a shoe support, a shoe clamp mounted for movement toward and from position to clamp a shoe against said support, an actuator having a stroke of predetermined extent, connections between said clamp and actuator including a light spring arranged, upon movement of the actuator, to move the clamp into engagement with a shoe resting 60 on said support, a pair of racks having relatively staggered teeth and connected with said clamp to be positioned by said movement of the clamp, a pair of pawls connected with said actuator to be moved thereby and arranged to have driving engagement with said racks, means for holding the pawls out of engagement with said racks until said actuator arrives at a predetermined point in its stroke, and a strong 65 spring interposed between said racks and said clamp through which the movement of the racks is transmitted to the clamp.
9. In a shoe holding jack, the combination of a clamp, an actuator, and mechanism 70 driven by said actuator toward said clamp for causing said clamp first to move into engagement with the shoe and then to apply a predetermined pressure to the shoe regardless of its size or thickness.
- In testimony whereof I have signed my name to this specification in the presence of 75 two subscribing witnesses.
